No. 766,170.

PATENTED AUG. 2, 1904.

E. CLIFF.
HOSE REEL.

APPLICATION FILED JUNE 22, 1903.

NO MODEL.

UNITED STATES PATENT OFFICE.

EDWARD CLIFF, OF NEW YORK, N. Y., ASSIGNOR TO CLIFF AND GILBERT COMPANY, OF NEW YORK, N. Y., A CORPORATION OF NEW YORK.

HOSE-REEL.

SPECIFICATION forming part of Letters Patent No. 766,170, dated August 2, 1904.

Application filed June 22, 1903. Serial No. 162,482. (No model.)

To all whom it may concern:

Be it known that I, EDWARD CLIFF, a citizen of the United States, and a resident of New York, in the county of New York and State of 5 New York, have invented certain new and useful Improvements in Hose-Reels, of which the following is a specification.

The invention relates to improvements in hose-reels, and particularly to improvements 10 in hose-reels of the character employed in buildings having a fixed water-supply apparatus to which the hose-reel may be permanently applied.

In the embodiment of my invention herein 15 presented the reel proper is mounted upon a hollow valve-casing which is connected with the water-supply pipe and upon which the reel may be freely revolved. The hollow valve-casing is inclosed throughout its main portion 20 by the hollow hub of the reel, and this hub intermediate the disks of the reel is provided with a hose-attaching nozzle, to which one end of the hose is removably connected and which communicates with the interior of the hollow 25 valve-casing.

In the preferred construction the hollow valve-casing is at its inner end provided with a valve-seat, and within the casing is provided a reciprocating valve to engage said seat and 30 cut off the water-supply from the hose or to be moved from said seat and permit the water to flow freely to the hose. The reciprocating valve within the valve-casing is connected with a threaded valve-stem which en- 35 gages the thread in the bonnet of the valve-casing, and upon the outer threaded portion of this valve-stem is provided an internally-threaded sleeve which keys with the hub of a hand-wheel capable of engagement and rotation with the reel and which sleeve may during 40 a portion of the unwinding of the hose from the reel travel outwardly on said stem without affecting the valve and then during the latter portion of the unwinding of the hose 45 from the reel become locked with the valve-stem, and actuate the latter to open the valve, the said valve, while being an automatic valve, thus not opening until a definite length of hose has been unwound from the reel. Upon the

valve reaching its full-open position the afore- 50 said sleeve will have passed entirely free of connection with the reel, and hence any then further movement of the reel will not affect the valve.

The present invention relates more especially to improvements upon the hose-reel described and claimed in Letters Patent of the United States No. 643,712, granted February 20, 1900, to Edward Cliff, and No. 661,953, granted November 20, 1900, to Edward Cliff, 60 and the said invention pertains to several novel features of arrangement, equipment, and construction rendering the hose-reel more efficient and convenient of operation, more durable and convenient of construction, and 65 less liable to be injured or strained by any improper manipulation of its parts.

The invention will be fully understood from the detailed description hereinafter presented, reference being had to the accompanying 70 drawings, in which—

Figure 1 is a side elevation, partly in central vertical section, of a hose-reel and connected parts constructed in accordance with and embodying the invention. Fig. 2 is a 75 vertical section of same, partly broken away, on the dotted line 22 of Fig. 1, the hand-wheel being omitted in Fig. 2 from the valve-stem. Fig. 3 is an inner face view, partly broken away, of the hand-wheel detached from the 80 valve-stem. Fig. 4 is a side elevation, partly in section and partly broken away, of the aforesaid hand-wheel, this figure being presented more particularly to illustrate the hub of said wheel. Fig. 5 is a detached sectional view 85 corresponding with Fig. 1 of the outer portion of the reel and its parts, this figure showing the sleeve on the valve-stem in side elevation and by dotted lines indicating the outer position of said sleeve; and Fig. 6 is a detached 90 end view of the valve-stem and the nut thereon.

In the drawings, 10 designates the usual water-supply pipe; 11, a valve-casing applied to the end of said pipe in the usual manner and comprising a horizontal cylindrical portion 12 and a vertical portion 13; 14, the bonnet closing the outer end of the portion 12 of said valve-casing; 15, a valve-stem carrying

the valve 16 within the portion 12 of the valve-casing and threaded to engage the internal thread of a sleeve 17, extending inwardly from said bonnet; 18, the stem for a vertically-acting valve 19 within the portion 13 of said valve-casing; 20, the usual hand-lever by which the valve 19 is moved vertically and which at its outer end is pivoted in the upper end of a customary link 21, which acts as a fulcrum for said lever; 22, the hub of the reel mounted upon the portion 12 of said valve-casing; 23, the disks of the reel, which are connected together by bolts 24, upon which the hose may be wound in a well-known manner; 25, a nut rigidly secured upon the outer threaded end of the valve-stem 15; 26, an internally-threaded sleeve mounted upon the outer threaded end of the valve-stem 15 and adapted to travel intermediate the bonnet 14 and nut 25, and 27 a hand-wheel whose hub 28 contains a polygonal bore adapted to pass upon and engage the correspondingly-formed outer surfaces of the sleeve 26 and which hub is also adapted to be placed into locking engagement with the outer disk 23, as hereinafter explained.

The horizontal portion 12 of the valve-casing 11 is formed with a valve-seat 29 for the valve 16 and is substantially inclosed by 30 the hub 22, which is adapted to turn thereon, said portion 12 constituting a support and axis for the reel proper. The portion 12 of the valve-casing is formed with openings 30, through which the water at the proper time 35 passes into the annular chamber 31, intermediate said portion 12 and the hub 22 and communicating with the hose 32, which will have its inner end secured to the hub 22 in a well-known manner.

40 The hub 22 in the present instance is formed at its ends with the shoulders 33, which, as shown in Fig. 2, are polygonal in outline, the flat surfaces of said shoulders 33 forming at their meeting-points the projections 34, which 45 I utilize in securing the disks 23 upon said hub 22. The disks 23 are formed with hubs 35, from which radiate the spokes 36, and which hubs are mounted upon the shoulders 33 of the hub 22, so that said disks and hub 50 22 may rotate together. The hubs 35 are recessed at 37, the recesses 37 being arranged to receive the projecting portions 34 of the shoulders 33, as shown in Fig. 2, and to co-operate with said projections 34 in locking 55 the disks 23 against rotation upon or independently of the hub 22. In assembling the hub 22 and disks 23 the inner disk 23 is set upon the inner shoulder 33 from the outer edge of the latter, so that the projections 34 60 of said shoulder may set within the recesses 37 of said disk, and thereupon the outer disk 23 is set upon the outer shoulder 33 of the hub 22, the projections 34 of this outer shoulder 33 entering the recesses 37 of the said 65 outer disk, and thereafter the bolts 24 are ap-

plied for tying the disks 23 together and binding their hubs 35 against the shoulders 33 of the hub 22. The shoulders 33, having the projections 34 co-operating with the recesses 37 of the disks 23, aid materially in rendering the reel as a whole extremely durable, and in addition the said features constitute a very simple and inexpensive means for effectually locking the hub 22 and disks 23 together. The recesses 37 are in line with the 70 spokes 36 of the disks 23, and this feature is important, because when the disks are placed upon the shoulders 33 of the hub 22 the holes in said disks for the bolts 24 will always be in proper alignment ready to receive said bolts. 80

There is no new feature presented in this application in the construction, arrangement, or operation of the valve-stem 15, valve 16, nut 25, and sleeve 26, since all of these features just enumerated are fully disclosed in the 85 aforesaid Letters Patent No. 661,953. The hand-wheel 27 is employed to co-operate with the nut 25 and sleeve 26 in the manner fully explained in the aforesaid Patent No. 661,953; but in the present instance the hand-wheel 27 90 is provided at the inner end of its hub 28 with novel means for automatically causing said hub to disengage itself from the bonnet 38 of the outer disk 23 at the proper time, so that any continued rotation of the reel after 95 the valve 16 has become seated may not act through the wheel 27 to twist off or strain the valve-stem 15, such rotation resulting in the wheel 27 moving outwardly from the bonnet 38 and leaving the reel free of said wheel, the 100 sleeve 26, and stem 15, said stem thus remaining unaffected by any motion which may be imparted to the reel. The means provided for effecting the automatic outward travel of the wheel 27 during the rotation of the reel after 105 the valve 16 has become seated comprises in the preferred construction spirally-inclined flanges 39, extending inwardly, Fig. 2, around the hole 40, formed at the center of the bonnet 38 of the outer disk 23, and spirally-inclined 110 flanges 41, formed at the inner end of the hub 28 of the wheel 27, the flanges 41 being more fully illustrated in Figs. 3 and 4. The flanges 41 on the hub of the wheel 27 are undercut 115 at their outer ends to form lips 42, as more clearly illustrated in Fig. 4, and when the wheel 27 is applied to the bonnet 28 of the outer disk 23 the said lips 42 will engage the under surface of the outer ends of the flanges 39 of said bonnet, and thereby serve to lock 120 the wheel 27 to said bonnet, this interlocking engagement of the wheel 27 with the bonnet 38 continuing during the movement of the reel in a direction to unwind the hose therefrom, this direction of movement being indicated by the arrow in Fig. 2, the reel then turning toward the left. Should, however, an attempt be made to turn the reel toward 125 the right while the valve 16 is in engagement with its seat 29 and the hub of the wheel 27 is 130

in engagement with the bonnet 38 of the outer disk 23, the motion of the reel will carry the inclined surfaces of the flanges 39 against the corresponding surfaces of the flanges 41 and force the wheel 27 outwardly upon the sleeve 26 and from its engagement with the bonnet 38, the first movement of the reel carrying the outer ends of the flanges 39 from under the lips 42 of the flanges 41 and then by a wedge action moving the wheel 27 directly outward upon the sleeve 26, thus freeing the wheel 27 from the reel and allowing the latter to be turned as much as desired without its movement at all affecting the valve-stem 15. In the construction shown in the aforesaid Letters Patent No. 661,953 the hand-wheel 27 when at its inward position was, in effect, locked to the reel and subject to the reel, even after the valve 16 became seated, and thus in the construction shown in said patent the movement to the right of the reel after the valve 16 had become seated would result in the hand-wheel 27 being turned with the reel and in straining or twisting off the valve-stem 15. In the construction shown in the aforesaid Patent No. 661,953 it was intended that the operator should after closing the valve 16 withdraw the hand-wheel 27 outwardly from the reel before winding the hose upon the latter; but this was frequently forgotten or neglected, with the result that the pressure applied to the reel, the latter acting as a long lever, would result in serious damage to the valve-stem 15. A further disadvantage of the construction shown in the aforesaid Patent No. 661,953 and which is corrected by the present invention was that a workman fitting up a building and having to apply the reel to the water-supply pipe would while the hand-wheel 27 was in engagement with the reel and the valve 16 in engagement with its seat use the disks of the reel instead of a wrench as a means for securing the reel and its valve-casing upon said pipe, this operation not injuring the reel while the valve-casing thereof was freely turning upon the end of the water-supply pipe, but straining or breaking off the valve-stem 15 after the said valve-casing had reached home upon said pipe, and said workman would then give the reel a further wrench to finally insure the secure attachment of said valve-casing upon said pipe, this further power applied to the reel being communicated through the hub of the wheel 27 and sleeve 26 to the valve-stem 15, and the latter being then incapable of further movement, straining, or breaking said stem. These objections to the construction shown in the aforesaid Patent No. 661,953 are remedied by the present invention, wherein any movement of the reel toward the right after the valve 16 has become seated will result in the automatic unlocking of the wheel 27 from the bonnet 38 of the outer disk 23. In the present instance I employ two of the flanges 41 on the hub of the wheel 27 and two

of the flanges 39 on the bonnet of the outer disk 23, so that the said hub may engage the said bonnet at opposite points, but with less satisfaction. One flange 41 and one flange 39 may be employed in lieu of the duplication of 70 said flanges.

In Fig. 1 I illustrate the parts of the reel and valve, with the valve 16 in its closed position and the hand-wheel 27 in engagement with the reel, the sleeve 26 being then at its 75 inward position. In the event of a fire the attendant will grasp the usual nozzle (not shown) at the end of the hose and run with the same toward the fire, this act resulting in the unwinding of the hose from the reel and the 80 rotating of the latter toward the left or in the direction of the arrow shown in Fig. 2. The rotary motion of the reel is communicated to the hand-wheel 27 and by the latter to the sleeve 26, the said sleeve 26 turning freely upon 85 the valve-stem 15 and traveling outwardly upon said stem and from within the hub 28 of the wheel 27, but not affecting or rotating said valve-stem 15 until a given amount of the hose shall have been unwound from the reel and 90 the said sleeve shall have passed into engagement with the nut 25, upon the happening of which the continued rotation of the reel, hand-wheel 27, and sleeve 26 will be imparted to the nut 25 and through the latter to the valve-stem 95 15 and valve 16, the latter being thus caused to travel outwardly from its seat to permit the water from the supply-pipe to enter the chamber 31 intermediate the hub 22 and the section 12 of the valve-casing. During the unwinding of the hose the valve 16 will not therefore be opened until such time as the sleeve 26 has traveled outwardly and passed into engagement with the nut 25. The sleeve 26 will be of such predetermined length that when the 100 valve 16 has reached its open position said sleeve will have entirely left the hub of the wheel 27 and be free upon the stem 15, this construction and relation of the parts being 105 desirable, so that any movement of the reel after the valve has become opened will not have any influence upon the valve or its stem 15, the wheel 27 during any such further movement of the reel merely turning with the bonnet 38 free of the sleeve 26 and having 110 no influence upon the latter. After the fire shall have been extinguished the attendant will drop the hose and return to the reel, and he will first withdraw the wheel 27 from the bonnet 38 and slide it outwardly upon the 115 sleeve 26 and nut 25, then together on the outer end of the stem 15, whereupon he will by manually turning the wheel 27 close the valve 16, this occurring before the hub of the wheel 27 reaches the opening 40 in said bonnet 38. When the hand-wheel 27 is in the outer position just above described, with the valve 16 closed, the reel may be rotated without 120 affecting the valve, and at such time the hose will be rewound upon the reel in the usual man- 125

130

ner. The attendant will then move the hub of the wheel 27 from off the nut 25 and permit said hub to engage the sleeve 26 only, whereupon he will by spinning the wheel 27 around rotate the sleeve 26 upon but without affecting the valve-stem 15 until said sleeve has entered within the bonnet 38 and reached the outer portion of the valve-casing and become arrested thereby. The attendant will then move the inner flanged end of the hub 28 of the wheel 27 into engagement with the bonnet 38 of the outer disk 23, and the reel will then be in its former normal condition (shown in Fig. 1) and prepared for any further emergency. If during the closing of the valve 16 the attendant should have inadvertently inserted the flanged end of the hub 28 into the bonnet 38 and forgot to withdraw the same, the act of winding the hose upon the reel would result heretofore in damaging the stem 15, and in the present construction should the attendant have thus carelessly left the hub 28 in locking engagement with the bonnet 38 the movement of the reel would result in the flanges 39 thereof ejecting the wheel 27 from its engagement with said bonnet, thus avoiding injury to the valve-stem 15. During the unwinding of the hose the engagement of the wheel 27 with the reel is maintained; but upon any reverse rotation of said reel the wheel 27 is forced outwardly therefrom by the coöperation of the spiral flanges 39 and 41, and this feature of the construction constitutes a portion of the present invention.

The horizontal tubular portion 12 of the valve-casing 11 serves as the support for the reel and is in one piece with the portion 13 of said valve-casing, and, as above described, within the said portion 13 is mounted a usual form of gate-valve 19, by which the water from the supply-pipe 10 may be cut off from the hose or admitted thereto, as may be desired. The valve 19 is to be operated manually, and prior to unwinding the hose from the reel the said valve 19 will in case of a fire be opened upwardly, so as to permit the water to flow into the portion 12 of the valve-casing and thence into the hose. The valve 19, operating-lever 20, and link 21 are well-known features and require no especial description. The valve 19 may be raised and lowered by a usual hand-wheel and threaded stem or by any of the well-known appliances for manually operating a valve. Since the portions 12 13 of the valve-casing 11 are in one integral piece, said casing is not only rendered durable, but contains no joints at which leakage could occur, and, in addition, the device as a whole becomes one self-contained article capable of being readily handled and conveniently applied to position upon the supply-pipe 10. The invention is not of course in every instance limited to the employment of the valve 19; but this valve is desirable, because it helps to prevent the turning on of the water to the hose 32 by careless

or idle persons whose curiosity might lead them to become interested in the reel, and when the valve 19 is employed it will of course be opened immediately prior to the unwinding of the hose from the reel. The valve 19 is also useful for cutting off the water from the portion 12 of the valve-casing in any instances in which it might be desired to remove the reel, bonnet 14, and valve 16 without detaching the valve-casing 11 from the supply-pipe 10.

What I claim as my invention, and desire to secure by Letters Patent, is—

1. The water-supply apparatus, and a valve-casing connected therewith, combined with the hose-reel mounted on said casing, the valve 16 for said casing, the valve-stem connected with said valve, the sleeve on said valve-stem and adapted to be moved outwardly thereon by the unwinding motion of the reel and to pass into locking engagement with said stem for opening said valve after the reel has completed a portion of its unwinding motion, the hand-wheel adapted to engage said sleeve and said reel and permit of the outward movement of said sleeve while it, said hand-wheel, remains in engagement with said reel, and means for automatically disengaging said hand-wheel from said reel upon the reverse rotation of the latter and while said valve 16 is seated, said means comprising inclined surfaces on said hand-wheel and reel whereby when said reel is reversed its inclined surfaces will ride against those of said hand-wheel and push the latter outwardly from the reel; substantially as set forth.

2. The water-supply apparatus, and a valve-casing connected therewith, combined with the hose-reel mounted on said casing, the valve-stem connected with said valve, the sleeve on said valve-stem and adapted to be moved outwardly thereon by the unwinding motion of the reel and to pass into locking engagement with said stem for opening said valve after the reel has completed a portion of its unwinding motion, the hand-wheel adapted to engage said sleeve and said reel and permit of the outward movement of said sleeve while it, said hand-wheel, remains in engagement with said reel, and inclined flanges respectively on said hand-wheel and said reel for automatically effecting the disengagement of said wheel from said reel upon the reverse rotation of the latter when said valve 16 is seated; substantially as set forth.

3. The water-supply apparatus, and a valve-casing connected therewith, combined with the hose-reel mounted on said casing, the valve 16 for said casing, the valve-stem connected with said valve, the sleeve on said valve-stem and adapted to be moved outwardly thereon by the unwinding motion of the reel and to pass into locking engagement with said stem for opening said valve after the reel has completed a portion of its unwinding motion, the

- hand-wheel adapted to engage said sleeve and said reel and permit of the outward movement of said sleeve while it, said hand-wheel, remains in engagement with said reel, and the 5 spiral inclined flanges 39, 41 provided upon said wheel and reel, respectively, for effecting the disengagement of said wheel from said reel when the latter is reversed while the valve 16 is seated; substantially as set forth.
- 10 4. The water-supply apparatus, and a valve-casing connected therewith, combined with the hose-reel mounted on said casing, the valve 16 for said casing, the valve-stem connected with said valve, the hand-wheel mounted over 15 said stem and adapted to be detachably connected with said reel, means for keying said wheel to said valve-stem so that said valve may be opened by the unwinding motion of said reel, and means for automatically disengaging said wheel from said reel upon the reverse motion of the latter, said means comprising inclined surfaces on said hand-wheel and reel whereby when said reel is reversed its inclined surfaces will ride against those of 20 said hand-wheel and push the latter outwardly from the reel; substantially as set forth.
5. The water-supply apparatus, and a valve-casing connected therewith, combined with the hose-reel mounted on said casing, the valve 25 16 for said casing, the valve-stem connected with said valve, the hand-wheel mounted over
- said stem and adapted to be detachably connected with said reel, means for keying said wheel to said valve-stem so that said valve may be opened by the unwinding motion of 35 said reel, and inclined flanges on said hand-wheel and said reel respectively for automatically effecting the disengagement of said wheel from said reel upon the reverse rotation of the latter; substantially as set forth. 40
6. The water-supply apparatus, and a valve-casing connected therewith, combined with the hose-reel mounted on said casing, the valve 16 for said casing, the valve-stem connected with said valve, the hand-wheel mounted over 45 said stem and adapted to be detachably connected with said reel, means for keying said wheel to said valve-stem so that said valve may be opened by the unwinding motion of said reel, and the spiral inclined flanges 39, 50 41 upon said wheel and reel respectively for effecting the disengagement of said wheel from said reel when the latter is reversed in motion; substantially as set forth.

Signed at New York, in the county of New 55 York and State of New York, this 19th day of June, A. D. 1903.

EDWARD CLIFF.

CHAS. C. GILL,
ARTHUR MARION.

It is hereby certified that the name of the assignee in Letters Patent No. 766,170, granted August 2, 1904, upon the application of Edward Cliff, of New York, N. Y., for an improvement in "Hose-Reels," was erroneously written and printed "Cliff and Gilbert Company," whereas said name should have been written and printed *Cliff and Guibert Company*; and that the said Letters Patent should be read with this correction therein that the same may conform to the record of the case in the Patent Office.

Signed and sealed this 23d day of August, A. D., 1904.
